CLAIM

I claim the ornamental design for a portable fishing rod holder, as shown and described.

DESCRIPTION

FIG. 1 is a top perspective view of the portable fishing rod holder showing my new design;

FIG. 2 is a bottom, exploded perspective view thereof;

FIG. 3 is a front side elevation view thereof;

FIG. 4 is a left side elevation view thereof;

FIG. 5 is a top plan view thereof;

FIG. 6 is a bottom plan view thereof;

FIG. 7 is a cross-sectional elevation view thereof taken along line 7-7 of FIG. 5; and,

FIG. 8 is a top perspective view of the portable fishing rod holder illustrating my new design in an environment with a fishing pole.

The broken lines and the areas within the broken lines shown in FIGS. 1, 2, and 8 depict portions of the article that form no part of the claimed design.
